UNITED STATES PATENT OFFICE.

THOMAS A. CONLON, OF SILVER SPRING, MARYLAND.

MECHANICAL LOADER FOR CANNON.

Application filed July 21, 1924. Serial No. 727,330.

(GRANTED UNDER THE ACT OF MARCH 3, 1883; 22 STAT. L. 625.)

The invention described herein may be used by the Government, or any of its officers or employees in prosecution of work for the Government, or by any other person in 5 the United States, without payment to me of any royalty thereon, in accordance with the act of March 3, 1883.

The subject of this invention is a mechanical loader for cannon.

10 In loading projectiles into heavy artillery at all angles of elevation, the weight of the projectile requires that mechanical assistance be resorted to in performing the ramming operation.

15 The present invention resides in utilizing the energy of recoil to store up energy to perform the loading operation, and the result is accomplished by associating a rammer with the recoiling portions of a gun and 20 adapting the rammer to return to battery, independently, to actuate a loading apparatus, enclosed in a projectile tray, to advance a projectile into the breech of the gun barrel.

25 According to the invention, a rammer is mounted with the gun so as to be retractable therewith, without interfering with other operations at the breech, and held in cocked position to be enabled to return independently of the gun. The rammer, when in 30 cocked position, is forward of the base of the projectile to be loaded, thus providing for a short recoil of the gun, while the finger of the rammer is so inclined as to maintain 35 proper clearance when the projectile is moved into alignment with the bore.

The loading apparatus is completely enclosed in a projectile tray and embodies an endless chain having a special link which 40 movable the entire length of the tray, when the chain is actuated through the instrumentality of the rammer, to advance the projectile with a uniform speed into the gun.

To these and other ends, my invention 45 consists in the construction, arrangement, and combination of elements, described hereinafter and pointed out in the claims forming a part of this specification.

A practical embodiment of my invention 50 is illustrated in the accompanying drawings, in which,

Fig. 1 is a view in side elevation of the improved loader;

Fig. 2 is a sectional view taken on the line 2—2 of Fig. 1; 55

Fig. 3 is a plan view of the loading tray with the cover plate and arms removed;

Fig. 4 is a sectional view taken on the line 4—4 of Fig. 3;

Fig. 5 is a sectional view taken on the line 5—5 of Fig. 3;

Fig. 6 is a view, part in side elevation and part in section, of the latch mechanism;

Fig. 7 is a sectional view taken on the line 7—7 of Fig. 6; 65

Fig. 8 is a sectional view taken on the line 8—8 of Fig. 3;

Fig. 9 is a detailed view partly in section of the special link; and

Fig. 10 is a fragmentary plan view of the 70 chain.

Referring to the drawings by numerals of reference:

The barrel 10 of a cannon is reciprocally carried by the usual mount comprising a 75 cradle 11, cradle side plates 12, and trunnions 13. Stationarily disposed between the barrel and left side cradle plate is a cylinder 14 supported and rigidly held as by brackets 15.

Mounted for reciprocal movement in the cylinder 14 is a rammer rod 16, terminating in a ram head 17, which normally extends beyond the breech end of the barrel. The ram head is formed with a finger 18, which 85 is disposed at an angle in the direction of the bore of the barrel.

The breech of the gun may be formed with a stepped upper left edge and in the depression thus formed is secured a guide collar 19, which embraces the rammer rod in front of the ram head 17 and serves as a support for the rod and as a means for retracting it during the recoil movement of the barrel to compress a spring suitably carried in the cylinder 14. 90

Attached to the cradle side plate 12, is a rearwardly extending overhead channel support 20, its rear portion carrying a guide plate 21, riveted to its under face. The free 100 end of the support 20 is secured to a bracket arm 22, which is conveniently fastened to the cradle side plate extension 23, as shown in Figure 1.

The guide plate 21 is formed to provide 105 a groove 24 to receive a complementary

tongue 25, formed on the ram head 17, for guiding the rammer rod in reciprocation.

A suitable mechanism for holding the rammer in cocked position is provided on the rear portion of the support 20, and embodies a pivoted latch 26 having a beveled face 27, normally projected into the path of the ram head by a spring 28. A lever 29, pivotally carried by the support 20, is engaged under the free edge of the latch whereby the latch may be raised to release the rammer.

During retraction of the rammer, the latch is tripped by the tongue 25 on the ram head and immediately returned by the latch spring to retain the rammer in cocked position during counter recoil of the barrel. It will be noted that no part of the rammer is in line with the bore to interfere with the extraction of the empty cartridge case.

It will also be seen in Figure 1 that the position of the finger 18, when the rammer is cocked, is some distance forward of the base of the projectile when in place to be loaded and, therefore, opposite a small diameter of the cartridge case. The inclination of the finger is such that clearance will be provided for the projectile as it is moved into line with the bore of the barrel.

A tray 30, designed to carry a projectile, is mounted for oscillatory movement, so that when in the upper position (as shown in dotted lines in Figure 2) the projectile is in position to be advanced into the barrel during the loading operation.

The tray is provided with brackets 31, each of which have a bent arm 32, mounted on a shaft 33 suitably supported in the cradle 11 of the cannon.

The tray is formed with a lateral extension 34, adapted to be closed by a cover plate 35, which may be secured thereto by bolts 36, the whole forming a casing provided with grooves for the reception of an endless chain 37 on sprockets 38, a reciprocable bolt 39, and a stationary chain 40.

The endless chain is provided with a special link 41, normally positioned at the rear sprocket and the link is formed with a projection 42, adapted to be extended into the tray through a slot 43, formed between the extension and the cover plate, so as to be in position to engage the base of a projectile during the loading operation.

For the purpose of operating the endless chain and imparting to it a more rapid rectilinear movement than that of the part furnishing the moving force, the bolt 39 has rotatably mounted therein a sprocket wheel 44, which is in mesh with both the movable and stationary chains.

The sprocket wheel 44 is provided with a lug 45, which extends through a slot 46 formed in the cover plate 35 and in position

to be contacted by the rammer finger 18, as seen most clearly in Figure 1, during the forward movement of the rammer. The special link on the endless chain will advance the round from its position at rest almost completely into the cartridge chamber while the rammer is traveling from cocked position to the breech end of the barrel. The round may be moved home by the chamfered face of a sliding breech block. 75

Any suitable means may be employed for restoring the bolt and endless chain to normal position, a preferred form as herein shown, consisting in forming the bolt 39 with an open end 47 for the reception of a pin 48 to which is secured one end of a coil spring 49, the opposite end of which is suitably fastened to the extension 34. 80

The tray is provided with a lip 50 for retaining the projectile until the commencement of the loading operation. 85

In operation, assuming that the rammer is in cocked position, the tray carrying a projectile is moved in line with the bore, the lever 29 is manually moved to release the latch allowing the rammer to be urged forwardly by its spring. During this movement, the rammer, through its finger, rotates the sprocket wheel 44, to actuate the endless chain 37, which through its special link 41 advances the round into the gun to a position where the remaining movement may be accomplished by the breech block. Any suitable buffer mechanism may be provided in the rammer cylinder for easing the forward movement of the loading mechanism. 95

During recoil of the barrel the rammer through the guide collar 19, is retracted to cocked position where it is held until manually released. 105

While in the foregoing there has been illustrated and described such combination and arrangement of elements as constitutes the preferred embodiment of my invention, it is nevertheless desired to emphasize the fact that interpretation of the invention should only be conclusive when made in the light of the subjoined claims. 110

I claim:

1. In combination with a cannon and its mount, a loading apparatus embodying, a tray movable into and out of alignment with the cannon at the breech end thereof, an endless chain within the tray, a bolt, a sprocket wheel mounted in the bolt and meshing with the chain, means for rotating the sprocket upon movement of the bolt, a rammer supported by the mount and recoilable under tension with the cannon, said rammer adapted to move the bolt from normal position, and means for returning the bolt to initial position. 120

2. In combination with a cannon and its mount, a loading apparatus embodying, a 130

- tray movable into and out of alignment with the cannon at the breech end thereof, sprockets at either end of the tray, an endless chain supported by the sprockets, a special link on 5 said chain normally held at the rear of the tray, a bolt, a sprocket wheel mounted in the bolt, and meshing with the chain, means for rotating the bolt sprocket upon movement of the bolt, and means recoilable with 10 the cannon cooperating with the bolt for actuating the chain.
3. In combination with a cannon and its mount, a loading apparatus embodying, a tray movable into and out of alignment with 15 the cannon at the breech end thereof, a projectile advancing mechanism carried by the tray, a rammer supported by the mount and recoilable with the cannon for actuating said mechanism, and a latch for holding the 20 rammer in cocked position at a point intermediate the ends of the tray.
4. In combination with a cannon and its mount, a loading apparatus embodying, a tray movable into and out of alignment with 25 the cannon at the breech end thereof, a projectile advancing mechanism carried by the tray, a rammer supported by the mount and recoilable with the cannon for actuating said mechanism, and a finger formed on the 30 rammer for engagement with said mechanism, said finger inclined in the direction of the bore of the cannon to permit movement of the tray.
5. In combination with a cannon and its 35 mount, a loading apparatus embodying, a
- tray movable into and out of alignment with the cannon at the breech end thereof, means carried by the tray for advancing a projectile the entire length of the tray, and means recoilable with the cannon for actuating 40 the aforesaid means.
6. In combination with a cannon and its mount, a loading apparatus embodying, a tray movable into and out of alignment with the cannon at the breech end thereof, means 45 carried by the tray for advancing a projectile with a uniform speed into the breach, and means recoilable with the cannon for actuating the aforesaid means.
7. In combination with a cannon and its 50 mount, a loading apparatus embodying, a tray movable into and out of alignment with the cannon at the breech end thereof, means carried by the tray for advancing a projectile from its position at rest into the breech, 55 and means recoilable with the cannon for actuating the aforesaid means.
8. A loading apparatus for cannon including, a tray, an endless chain carried by the tray for advancing a projectile into the 60 cannon at a uniform speed, and means recoilable with the cannon for actuating said chain.
9. A loading apparatus for cannon including, a tray, a projectile advancing 65 mechanism enclosed in the tray, and means recoilable with the cannon for actuating said mechanism.

THOMAS A. CONLON.
